Primary Examiner — Robin V WebsterCLAIM

The ornamental design for a spring tine, as shown and described.

DESCRIPTION

FIG. 1 is a perspective view of a spring tine embodying our design and being depicted as part of a pickup assembly of an agricultural implement for environmental purposes;

FIG. 2 is an enlarged perspective view of the spring tine as depicted in FIG. 1;

FIG. 3 is a side elevation view of the spring tine as depicted in FIGS. 1 and 2;

FIG. 4 is a perspective view of the spring tine shown in FIGS. 1-3, but with the other components of the pickup assembly being removed to show the spring tine alone;

FIG. 5 is a perspective view of the spring tine taken at a generally opposite angle than that shown in FIG. 4;

FIG. 6 is a bottom elevation view of the spring tine shown in FIGS. 1-5;

FIG. 7 is a side elevation view of the spring tine shown in FIGS. 1-6, with the opposite side elevation view being a mirror image thereof;

FIG. 8 is a top elevation view of the spring tine shown in FIGS. 1-7;

FIG. 9 is an end elevation view of the spring tine shown in FIGS. 1-7; and,

FIG. 10 is an end elevation view of the spring tine opposite that shown in FIG. 9.

The broken lines are directed to environment and/or are for illustrative purposes only. None of the broken lines form part of the claimed design.
